(57) **CLAIM**

We claim the ornamental design for display bins with pivotal doors, as shown and described.

DESCRIPTION

Reference is made to utility application Ser. No. 09/812,052 filed (concurrently herewith) by Curtis P. Taylor and Anthony V. Sainato entitled Stackable Display Bins with Removable Pivotal Doors, and to the following design applications filed concurrently herewith by the same inventors, the disclosures of all of which are incorporated herein by reference:

Doors and Doors with Pivotal Mounts for Display Bins, Ser. No. 29/138,730;

Display Bins, Ser. No. 29/138,731; and, Front Portions of Stackable and Stacked Display Bins Having Pivotal Doors, Ser. No. 29/138,733.

FIG. 1 is a top, front, and right side perspective view of a display bin with pivotal door showing our new design; FIG. 2 is a bottom, rear, and right side perspective view thereof;

FIG. 3 is a right side elevational view thereof, it being understood that the left side elevational view is a mirror image of the right side elevational view;

FIG. 4 is a front elevational view thereof;

FIG. 5 is a top plan view thereof;

FIG. 6 is a rear elevational view thereof;

FIG. 7 is a top, front, and right side perspective view of a second embodiment of a display bin with pivotal door showing our new design;

FIG. 8 is a bottom, rear, and right side perspective view thereof;

FIG. 9 is a right side elevational view thereof, it being understood that the left side elevational view is a mirror image of the right side elevational view;

FIG. 10 is a front elevational view thereof;

FIG. 11 is a top plan view thereof;

FIG. 12 is a rear elevational view thereof; and,

FIG. 13 is a top, front, and right side perspective view of a third embodiment of a display bin with pivotal door which is the first and second embodiments in a stacked condition.
